(57) **CLAIM**

The ornamental design for a napkin holder, as shown and described.

DESCRIPTION

FIG. 1 is a perspective view of a napkin holder showing my new design;

FIG. 2 is a top view of the napkin holder;

FIG. 3 is a front view of the napkin holder, the rear view being a mirror image thereof;

FIG. 4 is an end view of the napkin holder, the other end view being a mirror image thereof; and,

FIG. 5 is a bottom view of the napkin holder.

The broken lines in the drawing illustrate environmental matter and form no part of the claimed design.
